LATCH TRIPPING MECHANISM

Hugh W. Sanford, Knoxville, Tenn., assignor to
 The Sanford Investment Company, Wilmington, Del., a corporation of Delaware

Application December 31, 1948, Serial No. 68,677

11 Claims. (Cl. 214—58)

1

This invention relates to improvements in Latch Tripping Mechanisms, particularly for mine cars and other conveying devices having drop bottom doors for the discharge of the lading therefrom.

This invention is an improvement on the latch tripping mechanisms set forth in my prior applications, Serial No. 432,341, filed February 25, 1942, now Patent No. 2,399,708, granted May 7, 1946; Serial No. 571,170, filed January 3, 1945; and Serial No. 588,577, filed April 16, 1945.

In the door latch mechanisms set forth in my prior applications, the latch or latches that support the free edge of the door were adapted to be engaged from beneath the car by tripping mechanism mounted at the trackway, whereby a tripping member would be moved by engagement with the latch hook for movement of the hook with respect to the car or conveying device to a released position, thereby unlatching or releasing the door for dropping movement. The contact and tripping members utilized for such prior devices were disposed in side-by-side relation substantially in the same upright transverse plane, whereby the contact member connected with the tripping member would ride along the under surface of the car and control the movement of the tripping member in response to the contour of the under-surface of the car.

An object of this invention is to improve the construction of the tripping mechanism to provide for the location of the contact member and tripping member, or respective faces thereon, in the same upright longitudinal plane so these faces will act on the same portions of the under-surface of the car or conveying device, and the contact member will deflect the tripping member away from such under-surface in vertical alignment therewith against engagement by the tripping member, such as would interfere with the passage of the conveyance thereover.

Where the contact and tripping members are located in side-by-side relation as in my prior applications, occasionally some part of the car may engage the tripping member in its raised position which would not extend across the car far enough to engage the contact member, which thereby may interfere with the operation of the conveying device or dislocate parts of the tripping mechanism. Such danger would be eliminated, however, by locating the contact and tripping faces in the same upright longitudinal plane, whereby the contact face would engage any part of the conveyance that would otherwise engage the tripping face.

2

This object may be accomplished according to one embodiment of the invention by providing an engaging or contact face on a single tripping arm in the same upright longitudinal plane in such position as to ride along the under-surface of the car or conveyance and be pressed upward in position for the tripping face to engage and release the latch hook from supporting engagement with the bottom door.

A further object of the invention is to simplify and improve the construction of tripping mechanism by locating the engaging and contact faces on a single tripping arm, so as not to require separate laterally spaced faces or arms in side-by-side relationship, as provided heretofore. These tripping and contact faces may be formed one behind another in the same upright longitudinal plane and in such position that the contact face will engage the portion of the car structure, such as the end sill, to insure of carrying down the tripping face so as not to become entangled therewith. Furthermore, it is preferable that the supporting member for the contact and engaging faces be located so as to swing downward in a direction forwardly of the normal movement of the car which facilitates the swinging of the contact face away from the end sill structure rather than to increase its bearing contact therewith.

This embodiment of the invention is illustrated in the accompanying drawings in which:

Fig. 1 is a side elevation of a mine car and latch tripping mechanism;

Fig. 2 is a cross section through the tripping mechanism, showing portions of the mine car related thereto, other portions being omitted for simplicity of illustration;

Fig. 3 is a longitudinal sectional view therethrough showing the latch in engaged position;

Fig. 4 is a similar view showing the latch released;

Fig. 5 is a diagrammatic sectional view showing the tripping member in different positions with respect to portions of interconnected cars;

Fig. 6 is an enlarged sectional view partly in elevation showing a modified form of tripping member; and

Fig. 7 is a top plan view of a tripping member detached and showing a further modified construction.

This invention is shown as applied to a mine car of the general type set forth in my prior patent, No. 2,001,471, granted May 14, 1935, adapted for conveying coal or other loose lading from a receiving point to a tipple or other point

of discharge. The mine car is shown to be of the 4-wheel type, having three drop bottom doors interconnected for release in one-two-three order. This application of the invention is used, however, merely for purpose of illustration, and it is evident that the subject-matter of this invention may be applied to other types of cars, vehicles, and drop bottom conveyors in general, wherever it may be desirable to release bottom doors for dropping, in which the principle of this invention may be applicable.

The general structure of the car illustrated comprises a car body formed of side and end walls 1 and 2, rigidly secured together, the side walls 1 rising from a pair of oppositely disposed side sills 3 (Figs. 1 and 2), connected together at the ends of the car by means of combined end-sills and bumpers, designated generally at 4, and supported by bumper plates 5. The side and end-sills 3 and 4 comprise the frame structure of the car for supporting the lading body thereof, and between which is a bottom opening designed generally for discharge of the lading therethrough.

The car is supported upon wheels 6 and axles 7 connected with the side sills 3. The wheels 6 are adapted to travel on a track formed by a pair of laterally spaced rails indicated generally at R.

The car is shown of the character provided with three drop bottom doors adapted for discharge in one-two-three order from front to rear of the car. These doors are designated respectively by the numerals 8, 9 and 10. The forward door 8 is pivotally supported at its forward edge on a hinge rod, while each of the middle and rearward doors 9 and 10 is slidably and pivotally mounted on a hinge rod 12 extending between the frame structures at opposite sides of the drop bottom opening. Any other suitable door construction or arrangement may be used as desired.

The extreme forward edge of each of said doors 9 and 10, when in closed or latched position, projects laterally from the hinge rod 12, and is adapted to support the free edge of the next forward door. Then upon release of the rearward door, it may drop sufficiently to drag and move bodily rearward, thereby releasing the free edge of the middle door which will likewise drop and release the free edge of the forward door. This occurs usually just before the car reaches the tipple or bin, and permits dropping of the forward door in the bin for discharge of the lading thereon, as soon as room enough is provided in the bin therebeneath. The other doors drop in succession during the continued forward movement of the car over the bin or tipple in one-two-three order from front to rear of the car.

After dumping in passing over the bin or tipple, the doors are adapted to be closed by the usual door-closing rails located in the track. The doors may have indentations 13 in the under faces thereof to ride on the door-closing rails, which indentations would extend transversely of the doors throughout substantial portions of the width thereof. The doors are thus moved successively about their hinge rods to their closed positions, and the middle and rearward doors are pushed forward into wedging relation with the next forward door, adapted to be latched in closed position.

The foregoing car structure, to which this invention is shown applied as hereinafter described, is set forth more in detail in my prior patents, No. 2,001,471, May 14, 1935, and No. 2,036,644,

April 7, 1936, to which reference is made for a more complete illustration of the structure thereof.

As shown in Figs. 1 and 3 to 5, provision is made for latching the free edge of the rearward door 10 in closed position, thereby holding the several doors closed, to retain the lading in the car until the latching means is released for dumping. For this purpose, I have provided on the free edge of the rearward door 10, one or more supporting trunnions 14, one for each latch of said door. I prefer to use a pair of latches, each designated generally by the numeral 15 and spaced apart as indicated in Fig. 2, symmetrically with respect to the longitudinal center of the car. The latches 15 are pivotally mounted on a cross shaft 17 supported by brackets 18 secured to the adjacent bumper plate 5 of the car. Each of the latches 15 is preferably so constructed, or spring-pressed, as to be disposed normally in its door supporting position, or to return thereto automatically when disengaged for release of the lading.

Each of the latches 15 is provided with a seat 19 (Fig. 3) at the forward face thereof in position to receive the end of the adjacent trunnion 14 attached to the free edge of the rearward door 10. As shown in Fig. 3, the seat 19 is located on the opposite side of the vertical plane passing through the pivot axis of the latch 15 from the door 10, so that the weight of the door and the lading thereon tends to maintain the latched relation without any tendency for this weight to push the latch to one side.

Each of the latches 15 is provided, preferably, with a lateral pin 20 attached thereto and projecting through a slot 21 in the adjacent portion of the end-sill plate 5 (Figs. 3 and 4).

The foregoing structure corresponds generally with that set forth in my prior application for Door Latch Mechanisms, Serial No. 432,341, filed February 25, 1942, now Patent No. 2,399,708, granted May 7, 1946.

As shown in Figs. 3 and 4, the latches 15 are interposed between the free edge of the rearward door 10 and the adjacent end-sill structure 4, underneath a deflector plate 23 secured to the adjacent end wall 2. The latches 15 are so constructed and arranged that they are disposed wholly above the lower edges of the end-sills 4 of the car, and also, preferably, above the lower face of the rearward door, in protected positions. This prevents disarrangement of the latches or damage thereto in the event of wreckage of the car or from contact with obstructions in the trackway, as might occur in a mine, thus assuring adequate protection of the latches to maintain these in proper operative positions.

Each latch 15 is so mounted in protected position between the door 10 and the bumper 4 that a tripping space is provided between said door and the latch 15 in latched position for entry of a tripping arm therebetween.

To accommodate the tripping mechanism hereinafter described, each latch hook has its forward face, beneath the seat 19, provided with a notch 25 therein, having a lower engaging face 26 which slopes downwardly and forwardly relative to the length of the car. This face 26 is adapted to be engaged by the tripping arm as hereinafter described, and as shown in Figs. 3 and 4, to release the latch hook from supporting engagement with the door.

The tripping mechanism for the latches 15 is adapted to be mounted in the trackway between

the opposite rails R at a point adjacent the bin or other place of dumping. Since the latches 15 are laterally displaced symmetrically on opposite sides of the longitudinal vertical plane through the center of the car, a tripping device may be provided for each of the respective latches. Separate tripping devices should be provided where the latches are pivotally mounted independently on the cross shaft 17, although one tripping device may be used if the latches are secured to said cross shaft.

In the form shown, the tripping mechanism is mounted preferably on a base 27, shown in the form of a supporting plate securely mounted in suitable position in the trackway, preferably by being secured, as shown, upon the base flanges of the rails R. Secured to the under side of the supporting plate 27 are bearing boxes 28 and 28', the bearing boxes 28 being disposed adjacent opposite edges of the plate 27, while the bearing box 28' is in axial alignment therewith midway of the width of the plate.

Shafts 30 extend transversely between the bearing box 28' and each of the bearing boxes 28, and are arranged in axial alignment with each other on respective opposite sides of the center of the tripping device. The shafts 30 are independent of each other and capable of separate operation to provide for the independent unlatching of the respective latches, although one shaft may be used for the tripping elements of both latches, if they are to be unlatched simultaneously. In that event, only two bearing boxes will be required.

In the form shown, each of the shafts 30 has fixed thereon, as by welding, an upwardly extending tripping arm 31 which is inclined forwardly of the direction of movement of the car as illustrated in Fig. 3. The arm 31 supports on its upper forward end thereof a contact member 32, the upper face of which is somewhat wedge-shaped and is adapted to be deflected under the lower face of the car during movement of the latter over the tripping mechanism, so as to deflect this contact member beneath the car. The contact member 32 is shown as integral with the arm 31, although it may be a separate member secured thereto.

The forward upper end of the tripping arm 31 also carries an offset hook or bar 34 which has a wedge-shaped upper edge portion 35 in position to enter the notch 25 and engage the face 26 when the contact member 32 is substantially in its uppermost position, as shown in Figs. 3 and 4. The offset hook 34 acts as a tripping member and is disposed at the upper end of the arm 31 in the same upright longitudinal plane as the contact member 32, which contact member should be at least as high as the tripping member, or slightly higher, as shown.

The contact arm 31 is arranged to extend upwardly through the dumping plate 27 which is slotted at 36, to accommodate this arm, as shown in Fig. 2, for freedom of upward and lowering movement thereof. The arm 31 is mounted on each shaft 30 with the tripping member 34 in position to engage and actuate the latch, while the contact member 32 is guided under the bottom contour of the car passing thereover. The contact face of the member 32 has a sufficient slope relative to the contact edge of the latch 15, and is so yieldably mounted, that said contact member 32 will not disengage the latch but will be deflected therefrom as described. However, the tripping arm will be raised immediately to the

position shown in Fig. 3 for release of the latch 15 by the tripping portion 35.

Welded or otherwise secured to one side of the tripping arm 31 is an abutment 39 in position to engage the lower end of a limit screw 40. This screw 40 is threaded through the dumping plate 27 and through a threaded bar 41 fixed to the under side thereof, as shown in Fig. 3. This limit screw 40 may be adjusted up and down with respect to the dumping plate 27 and locked in its adjusted position by a jambnut 42. When properly adjusted, the limit screw 40 will be in position to engage the abutment 39, so as to limit the upward swinging movement of the tripping arm 31 and thereby limit the upward movement of the contact member 32 and tripping member 34.

These parts are held yieldably in elevated positions by a coiled spring 43, which is connected at one end with an eye-bolt 44, as shown in Fig. 1, attached to a bracket 45, suspended from the dumping plate 27. The eye-bolt 44 is adjustably connected at 46 with the bracket 45, as by nuts threaded on the end of the eye-bolt, for varying the tension of the spring. The opposite end of the spring 43 is connected to the lower end of the lever arm 47, extending downwardly from each of the shafts 30. The tension of the spring 43 should be sufficient to hold each set of tripping mechanism in its elevated position normally until depressed by the passage of the car or other conveyance thereover, whereby the contact and tripping elements will be deflected under the bottom structure of the car or conveyance to operative positions as shown in Figs. 3 and 4.

This action will position the tripping edge 35, so as to cause engagement thereof with the downwardly and forwardly inclined face 26 of the latch hook as the car passes over the tripping mechanism, and thereby will move the latch hook from its latched position, as shown in Fig. 3, to its unlatched position as shown in Fig. 4. This will release the trunnion 14 from the latch seat 19, so as to allow dropping movement of the rearward door 10 during the continued forward movement of the car. The release of the rearward door 10 will cause this to drop sufficiently so as to release the next forward doors 9 and 8, respectively, to discharge the lading when the car reaches the bin or tipple. At the same time, this forward movement of the car will cause the deflection of the contact member 32 and tripping edge 35 as will be evident from Fig. 4 to allow the bumper to pass thereover without obstructing such forward movement.

As the tripping edge 35 engages the face 26 of the latch hook during the forward movement of the car over the tripping mechanism, and swings the latch hook to its released position, the angle of the face 26 changes with respect to the angle of the tripping arm 33, while said arm 33 remains substantially in the same position. During this movement, the downward inclination of the face 26 forwardly of the car will tend to push upward on the tripping edge 35 to insure the maintenance of engagement of this tripping edge with the face 26 throughout the time that the latch 15 is being moved to its released position. Thus there is no tendency for the tripping edge to slip off the latch hook, but any tendency of relative movement between these edges is upward rather than downward, to increase the holding action of the tripping member on the latch until the latter is moved to its released position. Through the entire movement of the

hook, the co-efficient of friction between the tripping edge and the latch is sufficient to prevent the latch from slipping off the hook against the action of the spring 43 which is tending to hold the tripping edge 35 as high as it is permitted to go by the adjustable limit screw 40. Thus the latch is effectively released without any danger that the tripping member will be deflected without releasing the latch.

I have shown in Fig. 5, a diagrammatic view illustrating different positions of the tripping arm 31, contact element 32 and tripping face 35, with respect to different parts of cars coupled in interconnected relation, to illustrate how the tripping member will follow the contour of the under surface of the car in a wiping action therewith. The contact element 32 being at the same or slightly higher elevation than the tripping face 35 when they pass under the bumper structure 4, and in the same upright longitudinal plane, will locate the tripping face, so as not to catch in any part of the car which would destroy the tripping mechanism or cause damage thereto. Thus the contact element 32 will depress the tripping face 35 before the latter engages the forward face of the end sill and will insure that the tripping face will always clear obstructions on the under surface of the car.

This action is facilitated by the location of the pivot point 30 for the arm 31, in a direction rearwardly of the contact face 32, and tripping face 35, whereby the arm will drop in a direction away from the portion of the car engaged by the contact face, swinging downwardly in a direction toward the front of the car in its forward movement along the track, rather than rearwardly. This insures that the engagement of the contact face on the element 32 with the bottom of the end sill structure does not have a destructive effect on the tripping arm but pushes it down so that this arm will pass underneath the end sill structure without becoming entangled therein. The location of the pivot point 30 forward of the contact member 32 would not be practical for a mine car or other conveyance unless there is room enough for a considerable travel during the unlatching period.

I have also shown in Fig. 6, a modified form of tripping arm 31a, wherein the head portion 34a thereof which carries the tripping face 35, is so enlarged in its longitudinal dimensions as to engage the upwardly inclined rear edge of the door 10, when the face 35 is in its tripping position or in position for contact with the latch hook 15. This tends to support the door so that its weight bearing on the upper end of the contact arm will also deflect the arm and facilitate its dropping movement as soon as the latch is released from the free edge of the door.

A further modification is shown in Fig. 7, in which the tripping arm 31b has the head portion 34b of the same width as the arm. This provides the contact element 32b, and the tripping element 35b, of the same width as the body of the tripping arm. This enables the entire structure to be cast in one piece and to be of uniform width, if desired.

While I have shown two separate tripping devices for the respective latches spaced on opposite sides of the longitudinal center of the car and prefer to use such separate devices, a single tripping device may be used if the latches are fixed to the cross shaft 17. Generally, however, it is preferred to use separate tripping devices for the respective latches.

When the conditions of operation are such that the rear end of the car may be caused to slew sideways, so that it may be possible for one tripping device to release its latch before the other has unlatched its latch, the respective latches should be mounted independently for relative movement on the cross shaft 17, rather than fixed thereon. When this is so provided, each latch will be released independently and regardless of the way the car is slewed, and regardless also of any variation in the length of the respective tripping arms or in the set-up of the mechanism.

It will be appreciated also that any suitable form of latch may be used in place of the form illustrated, such for instance, as that set forth in my prior applications, Serial No. 432,341, and Serial No. 571,170, mentioned above, and the tripping face or member may be modified to conform thereto, without being limited to the form shown. The tripping face and contact face should be in the same upright longitudinal plane and may be co-extensive with each other in such position as to ride along the under-surface of the conveyance and to cause a tripping engagement with the latch hook or latch release member.

While the invention has been illustrated and described in certain embodiments, it is appreciated that other variations and changes may be made therein without departing from the invention, except as specified in the claims.

I claim:

1. In conveying mechanism, the combination with a trackway, a dumping conveyance movable along the trackway and including a lading body with a drop bottom door, and latch means for holding the door closed and movable to release the door for opening, of tripping mechanism mounted at the trackway and including latch release means in position to engage the latch means during movement of the conveyance over the tripping mechanism to release the door for opening, and contact means connected with the latch release means, and said contact means being in position for engagement by the under-surface of the conveyance during movement thereof over the tripping mechanism for controlling the releasing position of the latch release means, said contact means being substantially in the same longitudinal upright plane as the latch release means to engage successively the same longitudinal portions of the conveyance.

2. In conveying mechanism, the combination with a trackway, a dumping conveyance movable along the trackway and including a lading body with a drop bottom door, and latch means for holding the door closed and movable to release the door for opening, said latch means including engaging means for operating the latch means, of tripping mechanism mounted at the trackway and including latch release means in position to engage said engaging means during movement of the conveyance over the tripping mechanism to release the door for opening, and contact means fixed relative to the latch release means and located at substantially the same elevation as said latch release means and in the same upright longitudinal plane therewith when said latch release means is in latch engaging position to engage successively the same longitudinal portions of the conveyance, and said contact means being in position for engagement by the under-surface of the conveyance during movement thereof over the tripping mechanism for controlling the releasing position of the latch release means.

3. In conveying mechanism, the combination with a trackway, a dumping conveyance movable along the trackway and including a lading body with a drop bottom door, and latch means for holding the door closed and movable to release the door for opening, said latch means including engaging means for operating the latch means, of tripping mechanism mounted at the trackway and including latch release means in position to engage said engaging means during movement of the conveyance over the tripping mechanism to release the door for opening, and contact means fixed relative to the latch release means and located at substantially the same elevation as said latch release means and in the same upright longitudinal plane therewith when said latch release means is in latch engaging position, and said contact means being in position for engagement by the undersurface of the conveyance during movement thereof over the tripping mechanism for controlling the releasing position of the latch release means, and a tripping arm pivotally mounted in the trackway and supporting the latch release means and the contact means on the upper end thereof, and means yieldably urging the tripping arm upwardly to latch engaging position.

4. In conveying mechanism, the combination with a trackway, a dumping conveyance movable along the trackway and including a lading body with a drop bottom door, and latch means for holding the door closed and movable to release the door for opening, said latch means including engaging means for operating the latch means, of tripping mechanism mounted at the trackway and including latch release means in position to engage said engaging means during movement of the conveyance over the tripping mechanism to release the door for opening, and contact means fixed relative to the latch release means and located at substantially the same elevation as said latch release means and in the same upright longitudinal plane therewith when said latch release means is in latch engaging position, and said contact means being in position for engagement by the undersurface of the conveyance during movement thereof over the tripping mechanism for controlling the releasing position of the latch release means, and an arm pivotally mounted in the trackway for upward swinging movement relative thereto, said latch release means and contact means comprising abutments fixed on the upper end portion of the arm and spaced longitudinally thereof in positions for engagement respectively with the engaging means of the latch means and with the under-surface of the conveyance.

5. In conveying mechanism, the combination with a trackway, a dumping conveyance movable along the trackway and including a lading body with a drop bottom door, and latch means for holding the door closed and movable to release the door for opening, said latch means including engaging means for operating the latch means, of tripping mechanism mounted at the trackway and including latch release means in position to engage said engaging means during movement of the conveyance over the tripping mechanism to release the door for opening, and contact means fixed relative to the latch release means and located at substantially the same elevation as said latch release means and in the same upright longitudinal plane therewith when said latch release means is in latch engaging position, and said contact means being in position for

engagement by the under-surface of the conveyance during movement thereof over the tripping mechanism for controlling the releasing position of the latch release means, an arm pivotally mounted in the trackway for upward swinging movement relative thereto, said latch release means and contact means comprising abutments fixed on the upper end portion of the arm and spaced longitudinally thereof in positions for engagement respectively with the engaging means of the latch means and with the under-surface of the conveyance, and means connected with the arm and yieldably urging said arm in an upward direction.

6. Latch tripping mechanism adapted to be mounted in a trackway for releasing latch means of a drop bottom door on a conveyance, said tripping mechanism comprising a tripping arm adapted to be pivotally mounted for upward swinging movement, and latch release means and contact means mounted on the upper end portion of said tripping arm in the same upright longitudinal plane.

7. Latch tripping mechanism adapted to be mounted in a trackway for releasing latch means of a drop bottom door on a conveyance, said tripping mechanism comprising a tripping arm adapted to be pivotally mounted for upward swinging movement, and latch release means and contact means mounted on the upper end portion of said tripping arm in the same upright longitudinal plane, said latch release means and contact means being spaced apart longitudinally of the tripping arm.

8. Latch tipping mechanism adapted to be mounted in a trackway for releasing latch means of a drop bottom door on a conveyance, said tripping mechanism comprising a tripping arm adapted to be pivotally mounted for upward swinging movement, and latch release means and contact means mounted on the upper end portion of said tripping arm in the same upright longitudinal plane, said latch release means and contact means comprising abutments spaced apart longitudinally and substantially at the same elevation in position for engagement respectively with the latch means and the under-surface of the conveyance.

9. In conveying mechanism, the combination with a trackway, a dumping conveyance movable along the trackway and including a lading body with a drop bottom door, latch means for holding the door closed and movable to release the door for opening, said latch means including engaging means for operating the latch means, of tripping mechanism mounted at the trackway including an upwardly extending arm normally inclined relative to the trackway and extending lengthwise thereof, means pivotally mounting said arm at the trackway at the rearward end portion thereof relative to the direction of movement of the conveyance along the trackway, and abutments fixed on the upper end portion of the arm and spaced longitudinally of the direction of movement of the conveyance for engagement respectively with the latch engaging means and with the under surface of the conveyance to cause releasing movement of the latch means and to deflect the arm under the lower portion of the conveyance.

10. In conveying mechanism, the combination with a trackway, a dumping conveyance movable along the trackway and including a lading body with a drop bottom door, latch means for hold-

11

ing the door closed and movable to release the door for opening, said latch means including engaging means for operating the latch means, of tripping mechanism mounted at the trackway including an upwardly extending arm normally inclined relative to the trackway and extending lengthwise thereof, means pivotally mounting said arm at the trackway at the rearward end portion thereof relative to the direction of movement of the conveyance along the trackway, abutments fixed on the upper end portion of the arm and spaced longitudinally of the direction of movement of the conveyance for engagement respectively with the latch engaging means and with the under-surface of the conveyance to cause releasing movement of the latch means and to deflect the arm under the lower portion of the conveyance, said abutments being located substantially at the same elevation in the raised position of the arm, and means for yieldably urging the arm in an upward direction.

11. Latch tripping mechanism adapted to be mounted in a trackway for releasing latch means of a drop bottom door on a conveyance, said trip-
